UNITED STATES PATENT OFFICE.

CARL A. SIEWECK, OF NEW YORK, N. Y., ASSIGNOR TO REMINGTON ACCOUNTING MACHINE CORPORATION, OF NEW YORK, N. Y., A CORPORATION OF NEW YORK.

CALCULATING MACHINE.

Application filed January 8, 1923. Serial No. 611,293.

To all whom it may concern:

Be it known that I, CARL A. SIEWECK, citizen of the United States, and resident of the borough of Manhattan, city of New York, in the county of New York and State of New York, have invented certain new and useful Improvements in Calculating Machines, of which the following is a specification.

10 My invention relates to calculating machines, and especially to calculating machines capable of giving the algebraic total resulting from a series of additions and subtractions. One of the principal objects of my invention is to provide a clearance proof mechanism for algebraic totalizers. My invention may be regarded in some respects as an improvement on that set forth in the application filed by Arthur F. Poole, January 7, 1922, Serial No. 527,605 for improvements in calculating machines.

To the above and other ends my invention consists in certain features of construction and combinations and arrangements of parts, all of which will be fully set forth herein and particularly pointed out in the claims.

In the present instance I have shown my invention applied to that form of Remington accounting machine which includes a cross footer and which is shown and described in the patent to John C. Wahl, No. 1,270,471 dated June 25, 1918.

In the accompanying drawings,

35 Figure 1 is a partial conventional front elevation of a Remington machine of the kind above mentioned with my improvements applied thereto.

Figure 2 is a top view partly in section of a detail.

Figure 3 is a fragmentary isometric view of a part of the cross actuator.

Figure 4 is a fragmentary top plan view of a portion of the clearance proof mechanism partly sectioned away.

Figure 5 is a plan view of the algebraic totalizer in section on the line 5—5 of Fig. 6.

Figure 6 is a right-hand end elevation of said totalizer in section just inside the right-hand frame plate.

Figure 7 is a similar view in section on the line 7—7 of Fig. 5.

Figure 8 is a fragmentary view of the totalizer in section on the line 8—8 of Fig.

6, and looking in the direction of the arrows 55 at said line.

The Remington accounting machine is so well known and the calculating mechanism of it is so well described in the Wahl patent above referred to, that I have illustrated 60 only those fragments of the machine which immediately co-operate with the present invention. Said machine includes a Remington typewriter having mounted on its stationary framework the stationary framework of the Wahl calculating mechanism, the latter including a casting 15, a fragment of which is shown in Figs. 1 and 4. A main truck, not shown, is supported at the middle of the machine on wheels journaled 70 in said cross bar on frame-piece 15 and at its ends said truck is connected with the paper carriage of the typewriter, and on said truck may be mounted any desired number of vertical or columnar totalizers 16 75 and dummies 17, the latter consisting of a frame similar to that of a totalizer 16, but devoid of calculating mechanism. The machine also includes a cross truck 18 adapted to reciprocate to the extent of a single computing column, said cross truck having a hook 20 and a co-operating stop-piece 21, pivoted to the truck at 22 and adapted, when the carriage comes into an adding zone 80 in traveling from right to left, to engage 85 with a lug 23 constituting a part of the right-hand frame plate of one of the totalizers 16 or dummies 17, so that the truck shall be picked up by the lug. The cross truck 18 is drawn toward the right by a spring 19 90 and it normally occupies its right-hand position, and in said position the stop-piece 21 is depressed out of the path of the lugs 23, but the hook 20 stands in the path of said lugs. When the carriage is moved toward the left these lugs successively pick up said hook 95 and draw the cross truck toward the left and as soon as said truck begins to move, the stop 21 rises to the position shown in Fig. 1. At the end of a movement equal to the width of a computing column the hook 20 and stop 21 are cammed down out of the path of lug 23 and the cross truck immediately jumps toward the right ready to be picked up by the same or some other 100 totalizer or dummy.

The frame-piece 15 has secured to the right-hand part thereof the stationary

framework of the cross footing mechanism, which framework includes among other things a vertical end plate 24, a parallel plate 25, and a cross rod 26, Fig. 3, connecting said plates. A lever 27 is pivoted at 28 to the plate 24 and it is normally pressed toward the left by a spring 30. The truck 18 has an adjustable stop bar 31 which when said truck jumps back toward the right is adapted to strike the upper part of the lever 27 and press it back against the plate 24 and said truck is thus arrested. This lever 27 is not only part of the stop for limiting the right-hand movement of the cross truck but it is also a part of a locking mechanism which is fully described in the Wahl patent above referred to. Said lever has articulated therewith a long link 32 which is connected with the locking mechanism in the manner described in said patent. Said locking mechanism also includes a roller 33 indicated by dotted lines in Fig. 1, which roller is normally held up by a spring but is adapted to be depressed whenever one of the vertical totalizers or dummies passes over it, each of said totalizers and dummies having a certain track-way 34 mounted thereon for the purpose. The mechanism includes the usual numeral keys of the typewriter, which keys are connected with the Wahl actuator and which actuator includes a certain rocker or universal bar. The mechanism is so designed that when the roller 33 is depressed by a totalizer or dummy and the lever 27 is pressed back against the plate 24, then said rocker or universal bar is locked to warn the operator that he has got the carriage in an adding column but has not hooked up the cross truck, so that if the keys were operated the number would not be accumulated in the cross totalizer. This lock is thus referred to because I use it in connection with my clearance proof mechanism as will hereinafter appear.

The algebraic totalizer 35 is detachably mounted on the cross truck 18 in much the same way as is an ordinary Wahl totalizer, and some of its mechanism is, as shown in the present instance, identical with that of the Wahl totalizer. The frame of the totalizer 35 includes two side plates 36 connected together by various shafts, rods and bars, in accordance with the same general principles according to which Wahl totalizers are constructed and in some instances with exactly similar parts to those of a Wahl totalizer. Thus the rear parts of said plates 36 are made with the usual dove-tail formation so that they fit over the dove-tail cross truck 18. A rock shaft 37, having a finger piece 38, is pivoted in said frame plates precisely as in a Wahl totalizer, except that for reasons that will hereinafter appear, said finger piece is at the left-hand instead of

the right-hand side of the totalizer. Said shaft has on it a pair of hooks 40, which hook over the truck 18 and one of which is provided with a tooth 41 working in a notched plate 42 secured to the front face 70 of the cross truck 18. The hooks 40 are pressed against the dove-tail of the truck by the usual spring, not shown.

A rod or shaft 43 is secured at its ends in the plates 36 by means of screws 44, Fig. 75 8, and on said shaft are journaled any desired number of carrying wheels 45. As here shown these wheels are identical in construction and location and function with the carrying wheels of a Wahl totalizer. They are adapted to mesh with the cross master wheel 46 which drives them, and they carry each to the next of higher order by means of Geneva wheels 47 mounted on levers 48, which levers are pivoted on cross bars 50 and 51, these levers 48 extending down below the totalizer at the rear thereof into position to be operated by the regular Wahl auxiliary master dog 52. With certain exceptions which will be mentioned hereinafter these levers are identical in construction, function and mode of operation with levers of a Wahl totalizer. In the upper part of the totalizer there is a cross frame bar 53 having adjustable stop screws 54 for the upper ends of the levers 48 and these cooperate with the usual safety bar 55 pivoted in the side plates 36 at 56. Said levers are controlled by springs 57 connected to cross rods 58, these parts being 100 substantially like parts of the Wahl machine. Stationary bars 60 extend across the totalizer in position to align the Geneva wheels 47 whenever the latter are lifted out of engagement with the carrying wheels 45. The carrying wheels 45 drive a set of intermediate gears 61 journaled on a shaft 62 supported by the side plates 36. These wheels are made larger than the intermediate gears of an ordinary Wahl totalizer and 110 have twenty teeth.

In order to provide for algebraic calculation there are two sets of dials or numeral wheels, an upper set 63 for positive numbers and a lower set 64 for negative numbers, 115 said wheels being journaled respectively on cross rods 65 and 66. The individual dials may be of the usual Wahl construction except that the lower dials 64 have the numerals arranged thereon in an order 120 the reverse of that used on the ordinary totalizer. Each of the dials 63 and 64 has a pinion 67 meshing with one of the intermediate gears 61, so that each of said gears drives two dials, one of each set of dials. 125

As is well known, the direction of rotation of the master wheel 46 can be reversed, said wheel turning in the direction of the arrow in Fig. 3 for addition, and in reverse direction for subtraction. The re- 130

versal of this master wheel can be effected either manually or automatically, the automatic means including certain subtraction cams 68 mounted on the vertical totalizers 16 and dummies 17, and a follower roller 70 mounted on an arm 71 and normally pressed up by a spring but adapted to be depressed by said cams. In Fig. 1, the machine is shown arranged for work on a ledger sheet in which debit items are added into the first totalizer 16 and into the cross totalizer 35; credit items are added into the second totalizer 16 and subtracted in the cross totalizer; the new balance is written in the field defined by the left-hand dummy 17 and subtracted from the cross totalizer, and the old or pick-up balance is written in the column defined by the right-hand dummy 17 and added into the cross totalizer. This arrangement is shown merely by way of illustration, as many other arrangements can be used. It sometimes happens that the amounts subtracted from the cross totalizer exceed the amounts added in it. For example, if the machine is working on bank ledger sheets the depositor may check out more than he has on deposit. In that case the cross totalizer 35 should show an overdraft, and it is in order that this overdraft may be represented by plain figures that can be copied on to the paper in the third column that an algebraic totalizer is desirable on this particular piece of work.

I shall not go into any extended discussion of the principle of an algebraic totalizer, this being well understood, and the general principle of the particular one shown in the drawing is also well known, cross totalizers of construction similar in many respects to the present one being fully shown and described in certain prior patents to Arthur F. Poole, such for example, as Patent 1,296,118 dated March 4, 1919 and 1,301,318 dated April 22, 1919. Suffice it to say for the present that so long as the total indicated on the totalizer 35 is positive it can be read from the upper series of dials 63 and when said total is negative it can be read from the lower series of dials 64. Algebraic totalizers are preferably provided with shutters and I have shown herein two such shutters. The shutter 72 for the dials 63 extends across the said series of dials and is adapted to align with the sight-openings 73 in the casing plate 74 of the totalizer so as to conceal the dials 63 as shown in the drawings, and is also adapted to swing downward to display said dials. The cylindrical part of the shutter is supported by two end plates 75 pivoted on the shaft 65. The other shutter 76 is similarly adapted on occasion to align with the sight-opening 77 for the dials 64 to conceal said wheels and to swing down to the position shown in the drawings to display said dials;

and said shutter has end plates 78 pivoted on the shaft 66.

In order to shift the shutters 72 and 76 and in order to insert the "fugitive" "1" which it is necessary to add or subtract when the totalizer passes through zero, a handle 80 screwed on the end of a lever 81 is provided. This lever has a hub 79 pivoted on the shaft 62 and it projects from the front of the totalizer through a slot 82 in the casing. The construction is such that when this handle is moved from its upper to its lower position it shifts the shutters to conceal the negative dials 64 and to expose the positive dials 63 and this motion of the lever also adds "1" (positive) into the totalizer; and when the handle is moved from its lower to its upper position shown in the drawing it reverses the shutters to exhibit a negative total on the lower dials 64 and subtracts "1" in the totalizer. The precise construction of this lever can be varied but as here shown the main part of it is made of sheet metal and its hub 79 has mounted thereon a triangular piece 84 which is rigidly connected with the lever 81 by means of said hub and also of two posts 86 and 87, the first forward of the shaft 62 and the last behind said shaft. The right-hand end piece 78 of the shutter 76 has a notch which embraces the post 86, and said end piece also has a pin 85 which is embraced by a similar notch in the end piece 75 of the shutter 72 so that an operation of the handle 80 shifts both shutters. When said handle is in its upper position shown in the drawing the lower dials 64 are visible and when said handle is moved to its lower position the reading is from the positive dials 63.

The "fugitive" "1" is inserted by devices operated by the post 87. The part immediately operated by said post is a structure including a hub 88, Fig. 8, journaled on the right-hand end of the rod 43. This hub has rigidly mounted thereon an outer plate 90 and an inner plate 91 and it has a reduced part on which is loosely pivoted a third plate 92.

The plates 90 and 91 are rigidly connected at their lower parts by a post 93 having its ends reduced and riveted into said plates as shown in Fig. 8. The plate 91 has an arm extending upward and forward and bifurcated to embrace the post 87, thus interlocking this pivoted structure with the lever 81 so that said structure rocks with the lever 81 but in the opposite direction. Said plate 91 also has an arm or nose 94 (Fig. 7) extending upward and rearward and co-operating with a V-shaped point or nose 95 on a lever 96, which is pivoted on the frame rod 50 and is controlled by one of the springs 57 and co-operates with one of the stop screws 54, the same as the ordinary transfer levers 48; but this lever 96 does not extend

downward into position to be operated by the master dog 52. It is on the contrary operated by the nose 94 which is rounded for the purpose. The construction is such that the spring pressed lever 96 will retain said nose 94 and consequently the plates 91, etc., and the hand lever 81 in either of the two positions to which they can be set; but when force is applied to the lever 81 the lever 96 will yield and allow the parts to move to their alternative positions.

The plate 92, which is loosely pivoted on the hub 88, has two depending arms spaced apart as shown and embracing the post 93 but with lost motion so that said plate 92 is obliged to partake of the swinging of the plates 91 and 90 but has a limited motion independently thereof. This plate 92 has a nose or cam part 97 which lies by the side of the nose 94, the end of said cam part being concentric with the shaft 43, and of a suitable length for the purpose about to be described. Co-operating with this nose 97 is a nose 98 formed on a plate 100 lying beside the lever 96 and riveted thereto at 101 and therefore constituting in effect a thickening of a part of said lever 96, the effect being to thicken said lever so that its nose can co-operate not only with the part 94 but also with the part 97. In Fig. 7 the part 100 is sectioned away but the outline of it is indicated by broken lines. Beginning with the parts in the position shown in Fig. 6, if the handle 80 be moved downward the noses 94 and 97 will move toward the rear of the machine. The lever 96 will be cammed upward by the arm 94 but once elevated it will not immediately drop because the nose 98 will be held up by the cam dwell 97 until the lever 81 has almost completed its motion, when the nose 98 will pass off of the dwell 97 and will cam the nose of plate 92 towards the front of the machine. As this plate is loose on the hub it will move quickly and allow the lever 96 to be drawn down by the spring 57 with a snap. The construction shown in the patent to Arthur F. Poole, No. 1,301,318 has devices similar in principle to those just described and the function of said devices is explained in said patent.

It will be perceived that the relation of the lever 96 and the nose 94 is such that said lever 96 holds the plate 91 firmly at the limit of its motion in either direction.

In order to add or subtract "1" whenever the lever 81 is operated there is pivoted on the shaft 43 between the plate 91 and the units carrying wheel 45 a gear segment 102, Figs. 7 and 8, and this segment has two pins 103 projecting therefrom one on each side of the arm 94 but spaced apart so that the distance between them is greater than the width of said arm. When the handle 80 is in its upper position said arm 94 presses

the forward pin 103 firmly against a stationary pin 105, Fig. 7, projecting inward from the right-hand frame plate 36 and thus holds the segment 102 in the position shown in Fig. 7. When the handle 80 is pulled downward the arm 94 moves toward the rear of the machine and during the first part of its motion it does not operate the segment 102 but in the last part of its motion it engages the rear pin 103 and moves it toward the back of the machine until arrested by another fixed pin or post 104, also projecting inward from the plate 36. Said arm 94 will be firmly held in this position by the lever 96. The segment 102 has on its upper part a series of gear teeth corresponding in position and pitch to some of the gear teeth of the carrier gears 45 and the construction is such that an operation of the handle 80 moves said segment to the extent of one tooth, in positive direction when the handle is moved downward and in negative direction when the handle is moved upward. The motion of the segment 102 is communicated to the units wheel 45 by means of a Geneva pinion 106, Figs. 5 and 7, in all respects like the ordinary Wahl transfer pinions and mounted like them on one of the levers 48. This Geneva pinion has the usual scalloped middle part of greater diameter than the gear-toothed part and this enlarged scalloped portion is functionless except that it co-operates with the aligning bar 60 when the pinion is raised out of engagement.

I have shown the algebraic totalizer 35 occupying the position of the cross totalizer in the Wahl mechanism. In the Wahl machine, the cross-totalizer is usually freed from the vertical totalizer in that step of the carriage which immediately follows the writing of the digit in the lowest denominational position, and said totalizer is free of the master wheel 46 when it occupies its normal right-hand or jump-back position. When the handle 80 is operated it operates the lowest register wheel and this may result in carrying through to wheels of highest order. This handle should therefore never be operated when the totalizer is in engagement with the master wheel. To prevent it from ever being so operated means are provided for locking the handle 80 except when the totalizer is in its right-hand position free of the master wheel. To this end the plate 90, which it will be recalled is positively connected with the handle 80, is prolonged so as to form a rear stop surface 107 and a front stop edge 108, and these surfaces or edges interlock with a flange 110 bent off from a bar 111, Fig. 3, which bar has two arms 112 and 113 secured respectively to the frame plates 25 and 24 by screws 114 and 115, both of these being screws already present in the Wahl machine. Said Wahl ma-

chine also ordinarily includes a locking tooth 116 bent up from a piece of sheet metal 117 secured to the frame plate 25 by the screws 114. This locking tooth is in alignment with 5 one of the teeth of the master wheel 46 and during the operation of the machine said tooth engages and locks the carrying wheel 45 of next lower order than the one engaged at the time by the master wheel. The flange 10 110 constitutes a sort of continuation of the locking tooth 116 but at a lower level so that said flange does not lock the carrying gears 45 but does prevent motion of the plate 90 and consequently of the handle 80. The two 15 110 stop surfaces 107 and 108 are so disposed that when the handle 80 is in its lower position the stop surface 107 will ride just in front of the flange 110 and when said handle is in its upper position the edge 108 will ride 20 just behind said flange as shown in Fig. 6. In either event once the plate 90 gets into engagement with the flange 110, as it does whenever the totalizer is in engagement with the master wheel, the handle 81 cannot be 25 shifted. Said flange terminates at 118, Fig. 3, so that when the totalizer is in its right-hand position where it is out of engagement with the master wheel, the handle 81 is free to be operated.

30 In order to notify the operator when to shift the handle 80 the highest register dial in each of the series 63 and 64 has been marked with colors instead of digits, the dial showing a red spot when it is in its "9" position.

35 The mechanism thus far described is not of my invention. The Wahl mechanism, except for the totalizer 35 and the locking flange 110, is of the ordinary construction 40 heretofore employed and described in Patent No. 1,270,471; and the algebraic totalizer is substantially the same in principle as that described in the Poole application hereinbefore referred to and it is substantially the 45 same in construction, except for a few minor changes. In said Poole application the two shutters are both worked directly by the lever 81 instead of in the manner herein shown. Also I have shifted the shafts 65 50 and 66 about the shaft 62 as a center in a direction forward and downward in order to make room for certain devices of my invention to be hereinafter described.

55 Clearance proof mechanism for an algebraic totalizer of the kind herein described must of necessity differ from that which is applicable to an ordinary totalizer, for the reason that positive zero and negative zero correspond to different positions of the gearing. When one of the dials 63 has its zero 60 registering with the sight-opening the corresponding dial 64 has the "9" registering with the sight-opening and, vice versa, when one of the dials 64 has its zero on the reading line the corresponding dial 63 has a "9" on

the reading line. What is the zero position of the gearing therefore depends on which set of dials is under consideration. In providing mechanism, such, for example, as 70 feeler mechanism to test the state of the totalizer as to clear or not clear, it is therefore necessary to provide some selective scheme to distinguish between the two kinds of zero. Mechanism having this selective 75 power or property is shown in the Poole application hereinbefore referred to. It is the principal object of the present invention to provide improved mechanism having the property described.

The Remington accounting machine as 80 sometimes constructed includes clearance proving mechanism for the cross totalizer. This mechanism includes a lever 120, Fig. 1, which, at the time when said cross totalizer should be clear, is adapted to be swung to 85 the right by a spring 121 to actuate the locking mechanism hereinbefore referred to. The lever 120 is pivoted at 122 to a sheet metal framepiece 123 secured to the end of the casting 15 and it has at its lower end a 90 lug 124 bent off therefrom in position to actuate the lever 27. A button 125 on said lever 120 is used to restore the lever to its normal unlocking position. The lever 120 is normally held in its said unlocking position by a latch consisting of a bell crank 126 pivoted to the framepiece 123 at 127 and normally held up by the spring 121 into latching engagement with a lug or ear bent 95 backward from the upper end of the lever 120. The latter lever can be released by rocking the latch 126. This is done in that step of the carriage immediately following the writing of the last digit in the third column by means of a push wire 128, the 100 left-hand end of which is articulated with the rearwardly extending arm 130 of a bell crank which also has a leftwardly directed arm 131. This bell crank is bent up out of sheet metal in such a way as to give it bearing at two places spaced apart on a stud 132 secured to the horizontal overhanging part 133 of a bracket or framepiece which also has an upstanding part 134 and a horizontal part 135, the last secured to the casting 15 105 near the middle of the machine by screws 136. At the middle of the machine said casting has an upright and overhanging bracket 137 carrying amongst other things a pointer 138 which co-operates with scale 110 marks on the several vertical totalizers and dummies. The dummy 17 which in this particular instance locates the third column, has secured on top thereof by means of screws 140 a bar 141 which extends to the right of 115 said dummy to a sufficient distance to compensate for the fact that the lever arm 131 is not quite in the middle of the machine, said arm projecting above the right-hand dummy 17. The bar 141 has its right-hand 120 125 130 135 140 141

end bent up to form an arm 142, the rear end of which is beveled on its left-hand side to act on the beveled right-hand side of a dog 143, which dog is pivoted at 144 to the bell 5 crank arm 131. The dog 143 is urged in clockwise direction, Fig. 4, by a spring 145, its motion in that direction being limited by a stop pin 146 on the dog engaging the rear edge of the lever arm 131. On the return 10 motion of the carriage the abrupt edges of arm 142 and dog 143 engage each other with the result that the dog is deflected toward the right to let the arm 142 pass it without operating the bell crank, but when the carriage 15 is stepping toward the left, the beveled surfaces of parts 142 and 143 engage as shown in Fig. 4. The parts are shown in Figs. 1 and 4 in position for writing the last digit in the "balance" column. When said 20 last digit is written the carriage takes a step to the left and the arm 142 forces the dog 143 and bell crank arm 131 toward the rear of the machine, rocking arm 130 toward the right and tripping the latch 126, whereupon 25 the lever 120 immediately operates the lock lever 27. The bell crank 130, 131 is immediately restored to its normal position by a suitable spring 147. Means are provided to immediately restore the lever 120 to its normal 30 position in case the cross totalizer is clear, but not otherwise. The lever 120 has a horizontal arm 148 extending leftward and having at its free end an ear 150 bent back therefrom and notched and guided by a part 35 of the framepiece 123. This arm 148 has rigidly mounted thereon so as to be in effect a part thereof, a bar 151, said bar lying somewhat forward of the arm to which it is secured by screws 152 and posts 153. The bar 40 151 has its upper part bent forward to form a horizontal shelf to which at 154 there is pivoted a cam lever 155, to an ear of which is connected one end of a spring 156 the other end of which is connected to an ear bent off 45 from the bar 151. This spring tends to rock the leftward arm of the lever 155 toward the rear of the machine, its motion in that direction being limited by a foot 157 striking the arm 148. At its left-hand end this lever 155 50 is bent first downward and then rearward forming a lower shelf 158 having its two edges beveled to form an inverted V, the point of which is adjacent to the upwardly inclined end 160, Fig. 1, of the bar 151. 55 The Remington accounting machine as now being described has in the cross totalizer a lever or trippet similar to the lever or trippet 161 shown in the present case and consisting of an upstanding arm lying against 60 the right-hand frame plate of the cross totalizer, pivoted on the cross bar 51 of said totalizer and extending upward through a guide slot in the casing plate of the totalizer. This trippet is connected with clear- 65 ance testing devices in such a way that if

the totalizer is not clear, said trippet is forced to occupy a forward position, but if the totalizer is clear the trippet can swing a short distance toward the rear of the machine. The arm 148 and bar 151 are normally held as shown in Fig. 1 up out of the path of this trippet 161 but when the lever 120 is tripped as above described, these parts drop down to an inclined position. In the Remington accounting machine the same 70 step of the carriage that causes lever 120 to be released from its latch 126, also causes the cross truck 18 to be released from the dummy 17, and said truck and the totalizer 75 35 are immediately drawn toward the right by the spring 19. If the totalizer is not clear the trippet 161 on the jump-back of said totalizer toward the right, moves in a path a little forward of the bar 151 and does not restore said bar; but if said trippet occupies its rear position, which it can do only in case the totalizer is clear, then the end of said trippet acting on the inclined end 160 of the bar 151 restores the lever 120 to its normal unlocking position. It is the 80 function of the lever 155 and especially of its cam shelf 158 to transmit to the trippet 161 the power of the spring 156 to force said trippet to its rear position in case the totalizer being clear, that can be done. If the 85 totalizer is clear said trippet striking the inclined edge of the shelf 158 is deflected rearward so that its upper end comes under the incline 160 and disables the lock. If the totalizer is not clear said trippet is unable 90 to make the required motion toward the rear and the lever 155 is forced to yield forward as shown in dotted lines in Fig. 2 and the locking mechanism will then remain in operation. The clear signal mechanism above 95 described is not of my invention. 100

My invention consists in improved devices 105 within the algebraic cross totalizer 35, which devices control the trippet 161 in order to make it function in the manner above described. It is a well known property of algebraic totalizers of the general sort hereinbefore described that when such a totalizer 110 is cleared by writing and subtracting from it a negative total copied from the dials 64 and the train of gearing in each denomination of the totalizer is not brought back to the same position as when a positive total is 115 copied and subtracted from the dials 63. The position of the registering train that 120 corresponds to zero on the dials 64 is the position that corresponds to "9" on the dials 63. The problem of testing for clearance in a totalizer of this character is therefore complicated by this fact which may perhaps be 125 expressed by saying that negative zero is not the same position of the registering trains as positive zero. In the application of Arthur F. Poole hereinbefore referred to means 130 are provided and controlled by the handle 135

80 for automatically shifting a clearance testing feeler to one position for positive zero and to another position for negative zero, the same feeler and the same short 5 tooth on the same wheel being used in both instances. According to my invention I make a short tooth on one wheel in each denomination to test for positive zero, and a short tooth or another wheel of the same 10 train to test for negative zero, and use different feelers in the two instances. I provide selective mechanism controlled in the present instance by the handle 80, and in general by whatever part it is in the machine that 15 distinguishes between positive and negative totals, the construction being such that when testing for positive zero one set of short teeth and one feeler are used, and when testing for negative zero the other set of short 20 teeth and the other feeler are used. So far as I am aware it is new in mechanism of this character to provide different wheels in the registering train, one with a distinctive point (in the present instance a short tooth) 25 to test for positive zero, and the other with a distinctive point to test for negative zero; and it is also new to provide two feelers, one for positive and the other for negative zero; and it is also new to provide selective mechanism 30 for bringing two testing devices into use alternatively, depending on what kind of zero is to be determined.

In the present example of my invention each of the pinions 67 of the lower set of 35 dials 64 has one tooth 162 made shorter than the others and a feeler comb 163 is provided capable of co-operating with the teeth of the pinions 67 in such fashion that if one of the dials 64 does not stand at zero a long 40 tooth of its pinion 67 will be struck by a tooth of the comb 163; but if all of said dials stand at zero all of the short teeth 162 will face the teeth of the comb 163 and said comb can move further toward the shaft 66 than it can if some wheel does not stand at 45 zero. I also make each of the pinions 67 of the upper set of dials 63 with a short tooth 164 capable of co-operating with another comb 165 in the same general manner 50 as described with respect to the comb 163. I use one of these combs to test for positive zero and the other to test for negative zero. In the present instance the upper comb 165 is used for positive zero and the lower comb 55 163 for negative.

I have not deemed it necessary to illustrate in detail the precise construction of the feeler combs 163 and 165, devices suitable for the purpose having been constructed 60 in a variety of forms and one suitable for the purpose, except for slight modifications which will be mentioned, being shown in the patent to F. A. Hart, No. 1,414,639, dated May 2, 1922. These combs consist of 65 bars of metal extending lengthwise of the

totalizer and milled out, the comb 163 on its upper face and the comb 165 on its forward face, leaving narrow webs capable of moving into the spaces between the dials and contacting with the pinions 67. Each 70 of said combs is made at its ends with trunnions 166, which trunnions project through slots 167 in the frame plate 36 of the totalizer, Fig. 7. These trunnions 166 are the pivots of the feeler combs. The construction is such that if both combs be set with their trunnions in the upper ends of the slots 167, and if both combs be then rocked toward the dial pinions the lower comb 163 will co-operate with the lower pinions 67 to 80 test for negative clearance, but the upper comb will not reach the upper pinions 67. If on the other hand said combs be set with the trunnions in the lower ends of the slots 167 and be then rocked as described, the upper comb 165 will co-operate with the upper pinions 67 to test for positive clearance but the lower comb 163 will not move far enough to engage the lower pinions 67.

In order to shift the combs up and down 90 in the manner just described, I use selective mechanism comprising two two-armed cam plates or levers 170 mounted respectively on the two ends of the shaft 62 which carries the transmitting gears 61. Each of these cam plates has a hub 171 fixed to the shaft as, for example, by a pin 172, so that the two cam plates at the two ends of the shaft rock together. Each of said plates has in it two cam slots 173, Fig. 6, through which the trunnions 166 pass, said slots being so formed that when the plates stand in the position shown in Fig. 6 they hold said trunnions in the upper ends of the slots 167 but if said plates be rocked counter-clockwise in said Fig. 6 they will cam the trunnions to the lower ends of the slots 167. In other words, when these plates are set as shown in the drawings, the machine is in position for testing for negative zero but if they be rocked counter-clockwise the machine will be set for testing for positive zero. 100

In order to rock the selecting cam plates 170 in the manner described, they are suitably connected to that part of the machine 110 which determines positive and negative totals, this being in the present instance the hand lever 81. Said lever 81 is pivoted on the same shaft 62 that these cam plates are mounted on and the right-hand cam plate 170 lies just to the right of said lever. Said cam plate is formed with two radial edges 174 and a pin 175 projects from the lever 81 between these two edges, which edges are spaced apart so as to allow a suitable amount of lost motion to said pin. In Fig. 6 the lever is shown in its negative position and this pin, acting on the upper edge 174, holds the cam plates 170 in their negative position. If the lever be pushed down 120

to its positive position, the pin will engage the lower edge 174 and force the cam plates to their positive position. Said cam plates are arrested in their two positions by any suitable stops, those shown in the present instance consisting of two studs 176 projecting inward from the right-hand frame plate 36 to which they are riveted.

In the clearance testing operation the 10 feeler combs are operated by the trippet 161; that is to say, they are rocked about their trunnions 166 through suitable connections. The lower feeler comb has a lever arm 177 forced over its right-hand trunnion 166 and 15 secured against slipping on said trunnion by a dowel 178 and this lever extends rearward and has an operating pin 180 projecting toward the right from its rear end. The upper comb 165 has an operating lever 181 20 similarly mounted on its right-hand trunnion 166 and similarly secured by a dowel 182. This lever arm also extends rearward where it has projecting therefrom an operating pin 183. The pins 180 and 183 project 25 respectively into suitably formed slots 184 and 185 in a sheet metal lever 186 pivoted on a headed stud 187 riveted into the right-hand frame plate 36 as shown in Figs. 6 and 8. The lever 186 is so shaped as to 30 avoid interference with other parts of the machine but it has what amounts to a nearly horizontal rearward extending arm having in its free end a slot or notch 188 which is engaged by a stud 190 projecting from the 35 side of the forwardly directed arm of the trippet lever 161, which lever as shown in Fig. 6 has the general form of a bell crank. The upper arm of said trippet is shown in Fig. 6 in its forward position and the pin 40 190 therefore in its lower position. If said trippet be forced toward the rear of the machine with other parts standing as shown in Fig. 6, the pin 190 would move upward and rock the lever 186 counter-clockwise. 45 The slots 184 and 185 are so disposed that this motion of the lever 186 would rock the lower comb 163 clockwise and the upper comb 165 counter-clockwise. In other words, it would rock these combs toward their 50 respective sets of pinions 67. The parts are shown in their negative positions and the one lower pinion 67 shown, is in its zero position; and if all of the other pinions of this set are also in their zero positions the comb 163 would be able to rock as described 55 and the trippet 161 would be able to move toward the rear of the machine driven by the spring pressed cam 158. Said trip would, therefore, be caused to pass under- 60 neath the incline 160 and would release the locking devices above described, thus indicating that the totalizer had been cleared from a negative total. If, on the contrary, some one or more of the lower pinions 67 65 did not stand in their zero positions, one or

more of said pinions would present a long tooth to the feeler comb, which therefore would be unable to rock as described. The lever 186 and trippet 161 would be unable to move and the locking mechanism would remain in its locking position, thus notifying the operator that he had failed to clear the machine. If the handle 80 be moved to its lower or positive position, similar operations would ensue except that now it would be the upper comb 165 acting on the upper pinions 67 which would determine the operation of the trippet 161.

Various changes may be made in the details of construction and arrangement without departing from my invention.

What I claim as new and desire to secure by Letters Patent, is:—

1. In a calculating machine, the combination with a register capable of indicating positive and negative totals, of two clearance testing devices, one operative to test said register as to a positive state and the other operative to test said register as to a negative state.

2. In a calculating machine, the combination with a register capable of indicating positive and negative totals, of two clearance testing devices, one operative to test said register as to a positive state and the other operative to test said register as to a negative state; and selective means for operating said devices.

3. In a calculating machine, the combination with a register, of two clearance testing devices operative on said register at different points to test said register, one of said devices as to one state and the other of said devices as to another state.

4. In a calculating machine, the combination with a register, of two clearance testing devices operative on said register at different points to test said register, one of said devices as to one state and the other of said devices as to another state; and means for rendering one or the other of said devices operative, depending on the state for which test is to be made.

5. In a calculating machine, the combination with a register, of two clearance testing feelers, one operative on said register at one point and the other operative on said register at another point; means for operating said feelers; and means for rendering said feelers operative alternatively.

6. In a calculating machine, the combination with algebraic calculating mechanism capable of indicating a positive total and a negative total and having a part shiftable to one position for positive totals and to another position for negative totals, of two state testing devices so connected that one of them is operative in one position of said part and the other in the other position of said part.

7. In a calculating machine, the combination with registering mechanism, of clearance testing mechanism comprising two pivoted feelers, means for actuating both feelers, and means to adjust the pivots of said feelers to make them alternatively operative to test said registering mechanism. 70
8. In a calculating machine, the combination with algebraic calculating mechanism 10 having a part that occupies one position for positive totals and another position for negative totals of clear signal mechanism, two state testing devices, one for positive totals and the other for negative totals, and means whereby said part when in one position places said clear signal mechanism under the control of one of said devices and when in its other position places said clear signal mechanism under the control of the other of said devices. 20
9. In a calculating machine, the combination with registering mechanism, of two clearance testing devices, a part shiftable to two positions, and means connected with 25 said part for moving said devices toward and from the registering mechanism so that in one position of said part one of said devices is operative and in the other position of said part the other of said devices is operative. 30
10. In a calculating machine, the combination with registering mechanism, of two clearance testing feelers, a trippet connected with said feelers, means for shifting the control of said trippet from one of said feelers to the other, and clear signal mechanism controlled by said trippet. 35
11. In a totalizer, the combination with the register wheels, of two feelers for alternative co-operation with said wheels, a lever 186 connected with both feelers, two controlling devices 170 connected with the pivots at both ends of said feelers and shiftable to move said pivots and feelers alternatively 40 to operative and inoperative positions, and clear signal mechanism connected with said lever 186. 45
12. In a calculating machine, the combination of registering mechanism having a series of denominational trains of gearing, two wheels in each denomination having each a distinctive point, and means for testing said two wheels one for positive and the other for negative clearance. 50
13. In a calculating machine, the combination of a register having a series of denominational trains of gearing, two wheels in each denomination having each a distinctive point, and two feelers one co-operating with one of said two wheels and the other with the other of said wheels. 55
14. In a calculating machine, the combination of a register having a series of denominational trains of gearing, two wheels in each denomination having each a distinc- 60
- tive point, means shiftable to indicate positive and negative totals, and clearance testing means shiftable with said shiftable means to test one wheel in each denominational train for positive clearance and another wheel in each denominational train for negative clearance. 70
15. In a calculating machine, the combination with a master actuator and a totalizer having relative travel to different denominational positions, of a trippet, clearance testing devices controlling the operation of said trippet, and means for causing said devices to co-operate with one wheel of each denomination for positive clearance and with another wheel of each denomination for negative clearance. 75
16. In a calculating machine, the combination with a master actuator and a totalizer, said actuator and totalizer having relative travel, of clear signal mechanism, clearance testing mechanism controlling the action of said clear signal mechanism, and means brought into operation by such relative travel of the totalizer and its actuator to cause said clearance testing mechanism to test the position of one wheel of each denomination for positive clearance and another wheel of each denomination for negative clearance. 80
17. In a calculating machine, the combination of algebraic calculating mechanism including two sets of dials geared together, one set for indicating positive and the other for negative totals, devices shiftable to one position to display a positive total and to another position to display a negative total, and means connected with said shiftable devices for testing one of said sets of dials for positive clearance and the other of said sets of dials for negative clearance. 100
18. In an algebraic totalizer having a train of gearing in each denomination, the combination with said trains of gearing, of two feelers, one for co-operation with one wheel of each denomination and the other for co-operation with another wheel of each denomination, shiftable devices which when moved to one position move one of said feelers into and the other out of operative position, and vice versa, and means for operating said feelers to cause the one that is in operative position at the time to test for clearance, one of said feelers being adapted to test for positive and the other for negative clearance. 110
19. In a calculating machine, the combination with a master actuator and a jumping algebraic totalizer, of two clearance testing feelers in said totalizer, one for positive and the other for negative zero, means for shifting said feelers into operative position alternatively according to the kind of totals indicated at the time, and means operated by the jump-back of the totalizer for causing 115 120 125 130

the operative feeler to test said totalizer for clearance.

20. In a calculating machine, the combination with a jumping algebraic totalizer 5 having a registering train in each denomination, of clearance testing mechanism operative on one wheel of each denomination in case the totalizer is set to indicate a positive total and on another wheel of each denomination in case said totalizer is set to indicate a negative total, and means operated by the jump-back of said totalizer for caus-

ing said testing mechanism to co-operate with one or the other of said wheels in each denomination, depending upon the condition of the totalizer at the time. 15
